UNITED STATES PATENT OFFICE.

JULIUS NORD, OF THE HAGUE, NETHERLANDS.

TOURNIQUET.

Application filed February 12, 1925. Serial No. 8,613.

To all whom it may concern:

Be it known that I, JULIUS NORD, a subject of the Queen of the Netherlands, residing at The Hague, Netherlands, Buys Bal- 5 lotstraat No. 95, have invented certain new and useful Improvements in Tourniquets, of which the following is a specification.

This invention is an improvement in surgical appliances to stop bleeding in operations or accidents, and has for its object to provide an improved bandage of simple form to tie limbs instantaneously and in the most simple manner, which can be rapidly applied and removed again, and 15 which will remain securely in position.

I will explain the invention more fully with reference to the accompanying drawings in which:

Fig. 1 is an end view of the apparatus 20 showing the course of the straps, the spanscrew being in its most outward position.

Fig. 2 is a side view of Fig. 1.

Fig. 3 is a top plan view of Fig. 1.

Fig. 4 is a vertical section through Fig. 1, 25 showing the spanscrew in its most inward position, the straps being lifted into their extreme position.

Fig. 5 is a modification of the apparatus shown in Fig. 1, also drawn in end view and 30 the spanscrew being in its most outward position.

Fig. 6 is a side view of Fig. 5.

Fig. 7 is a top plan view of Fig. 5.

Fig. 8 is a vertical section through Fig. 5, 35 the spanscrew being in its most inward position.

Fig. 9 shows the apparatus applied to tie off a limb.

Referring to the drawings 1 (Figs. 1-4) 40 and 1^a (Figs. 5-9) designates a case, having two slots 2 and 3 underneath, through which respectively the ends of a fixed short strap 4 and a long movable strap 5 run, and a third slot 6 on the top, in which a strong wedge-shaped clamp 7 is placed. The inner end 45 of the short strap 4 is in a way fixed to the wedge 7, for example by sewing the strap round a pin 8 and then shoving it into the wedge. A hook 9 is fixed to the outer end 50 of the short strap 4. The long movable strap 5 is led through the upper slot and adjacent to the wedge 7, and an eye 10 is fixed to the lower end of this strap.

When both straps 4 and 5 are fixed round 55 the limb by means of the hook and eye 9, 10, such as represented in Fig. 9, the loop

can be tightened up by simply pulling the upper free end of the movable long strap 5 with the hand. The resultant pull is transmitted to the short strap 4 and thence to the wedge 7, thereby automatically securing the long strap 5 when it is released. Should it be necessary to instantly release the loop again for a moment, it is sufficient only to raise the wedge a little. The long strap 60 having been pulled the spanscrew 11, which is placed on one side of the case, is screwed inwardly to engage pin 12 (Figs. 1-4 and 9) or tube 12^a (Figs. 5-8) both carried by the screw, with the short strap 4 which in turn 65 engages with the long strap 5. As the screw 11 is operated the straps are drawn into the case to the positions shown in Figures 4 and 8 and the circulation of the blood is thereby stopped. A very exact degree of tension 70 can be maintained by the screw 11 which not only draws inwardly upon the straps but at the same time causes the wedge 7 to bind 75 against the strap 5 and thus secure it in its adjusted position.

As everybody who uses the apparatus perhaps is not strong enough to initially pull the movable strap 5 sufficiently with the hand thus necessitating a maximum adjustment of the screw 11 before the limb is tied off, it is proposed to provide a fourth slot 13 in the wall of the case 1 opposite to the screw. In the form of the invention shown in Figure 5 the side of the case opposite the screw is entirely open, as indicated at 13^a. 80

The apparatus enables a very quick and reliable underbinding of limbs. No india-rubber parts being used, the apparatus is always in a serviceable state. All parts can 85 be taken to pieces, as for cleaning, disinfecting, or substituting. The straps are preferably made of woven material and the other parts of nickel plated stainless material.

By using this apparatus, pinching of the 90 skin is entirely precluded.

Having now fully described my said invention what I claim and desire to secure by Letters-Patent is:

1. A surgical appliance to stop bleeding, 100 comprising a case having one slot on the top and two slots underneath, a wedge-shaped part mounted in the top slot and a short strap fastened to the wedge, passing through one slot underneath; a second strap passing through the second slot underneath and also through the top slot; a hook fastened to one 105

- strap and an eye fastened to the other one; and a screw by which the tension of the strap can be regulated and the wedge fixed, arranged at one side of the case.
- 5 2. A surgical appliance to stop bleeding, comprising a case having one slot on the top and two slots underneath, a wedge-shaped part mounted in the top slot, a short strap, a pin secured to said short strap and mounted in the wedge, the other end of said strap passing through one slot underneath; a second strap passing through the second slot underneath and also through the top slot between an edge thereof and the wedge; 10 a hook fastened to one strap and an eye fastened to the other one; and a screw by which the tension of the straps can be regulated and the wedge fixed, arranged at one side of the case.
- 15 3. A surgical appliance to stop bleeding, comprising a case having one slot on the top and two slots underneath, a wedge-shaped part mounted in the top slot, a short strap, a pin secured to said short strap and mounted in the wedge, the other end of said strap passing through one slot underneath; a second strap passing through the second slot underneath and also through the top slot between an edge thereof and the wedge; a hook fastened to one strap and an eye fastened to the other one; and a screw by which the tension of the straps can be regulated and the wedge fixed, arranged at one side of the case.
- 20 3. A surgical appliance to stop bleeding, comprising a case having one slot on the top and two slots underneath, a wedge-shaped
- part mounted in the top slot, a short strap, a pin secured to said short strap and mounted in the wedge, the other end of said strap passing through one slot underneath; and a second strap passing through the top slot between an edge thereof and the wedge; a hook fastened to one strap and an eye fastened to the other one; and a spanscrew for regulating the tension of the straps and fixing the wedge, arranged at one side of the case, such screw having means engageable with one strap to cause the latter to engage the other strap when said screw is operated, 25 said case having a fourth slot arranged in the wall thereof opposite to said means and through which said means and portions of the straps may be projected.
- 30 In testimony whereof, I have signed my name to this specification at The Hague, this twenty-second day of January, 1925.

JULIUS NORD.
